(57) **CLAIM**

The ornamental design for a display screen of an electronic device with graphical user interface, as shown and described.

DESCRIPTION

The patent or application file contains at least one drawing executed in color. Copies of this patent or patent application publication with color drawing(s) will be provided by the Office upon request and payment of the necessary fee.

FIG. 1 is a front view of a display screen of an electronic device showing my new design in a first embodiment; and, FIG. 2 is a front view of a display screen of an electronic device with graphical user interface showing my new design in a second embodiment.

The outermost broken lines of the electronic device illustrate environmental structure and form no part of the claimed design. The remaining black and gray dashed broken lines showing the display screen, icons, and partitions illustrate portions of the display screen and graphical user interface and form no part of the claimed design.
